PROCESS AND EQUIPMENT FOR GAS TURBINES

George Jendrassik, Budapest, Hungary

Application August 10, 1937, Serial No. 158,334
In Hungary February 13, 1937

14 Claims. (CL. 60—41)

In the case of gas turbines, in the first place in the case of gas turbines operating with constant pressure, the employment, for the purpose of raising the efficiency of the gas turbine, of heat exchange devices, constitutes a known method. The heat exchange device required for this purpose represents, however, a structure of such large weight, whereby its employment for many purposes—especially in case a low total weight of structure is required—is rendered more difficult.

With the aid of the working process according to the invention it is, even without any extensive employment of heat exchange devices, possible—whilst keeping weights low—to obtain total efficiencies of 25-45% and high outputs with as small dimensions as possible.

The gas turbine equipment necessary for this purpose, i. e. for the realization of the new process is composed of a compressor, of a turbine and of a firing chamber or combustion chamber arranged behind the compressor. According to the invention, in the compressor of the gas turbine the air is compressed to a certain advantageously chosen figure of pressure, following which combustion at constant pressure is produced so as to concentrate this combustion to a portion of the compressed air only or, heat is introduced into this portion of the air, which introduction of heat is followed, after having led this portion of the working medium together with the other portion thereof in a common gas current into the turbine, by a further heat introduction taking place in the first stages of the turbine, during expansion, advantageously in such a manner that this first part of the expansion should be approximately isothermal, whilst the expansion in the remaining stages of the turbine shall take a course which approaches more the adiabatic than the isothermal, any introduction of heat during the expansion in the said remaining stages of the turbine being preferably dispensed with.

By selecting the pressures, i. e. the pressure drops of the various sections of expansion in a suitable manner it is possible to obtain the high efficiency and relatively high specific output mentioned above, without having to raise the maximum mean temperature set up in the turbine above the limit to which materials of construction may still safely be heated, i. e. above about 600 to 700° C. This is possible as the said introduction of heat before the entrance into the turbine takes place in a portion of the compressed working medium only, at a temperature higher than the average temperature of the entrance into the turbine, this being necessary in view of

ensuring the safe ignition and the maintenance of the combustion of the fuel, whilst this high temperature is lowered by the other portion of the compressed working medium to a practically permissible value.

In order to enable the invention to be more readily understood, reference is made to the accompanying figures, of which

Fig. 1 represents the pressure-volume diagram of the working process;

Figs. 2, 3 and 4 are diagrams of the obtainable thermal efficiencies, and specific performances, respectively.

Figs. 5-5a and 6, respectively, are sections of two embodiments, shown by way of example, of the gas turbine suitable for carrying the working process into effect; Fig. 5a being a section along the section plane 5a—5a through the combustion chamber of Fig. 5.

Fig. 7 is a longitudinal section of an embodiment, shown by way of example, of an atomizer capable of being employed advantageously for the suitable control of the gas turbine; finally,

Figs. 8 and 9 are diagrammatical longitudinal sections of such types of design of the gas turbine in which a separate low-pressure turbine behind the turbine according to the invention is also provided.

In the diagram according to Fig. 1 representing a mode, by way of example, of carrying the process according to the invention into effect, the pressures set up in the working process are traced on the ordinate axis and the specific volumes of the gas on the abscissa axis— p_0 , v_0 and T_0 are denoting the initial pressure, specific volume and absolute temperature, respectively, of the gas drawn in by the compressor; p_1 , v_1 and T_1 are the corresponding figures relating to the condition of the gas when leaving the compressor, p_2 , v_2 and T_2 , this latter as a mean (equalization) temperature are the condition indicators of the gas after preliminary introduction of heat, whilst p_3 , v_3 , T_3 and p_4 , v_4 , T_4 are the condition indicators of the final condition of the expansion taking place in the turbine during further heat introduction at practically constant temperature, and those of the condition at the discharge from the turbine after the (adiabatic) expansion, respectively. p_4 and p_0 are, in general, equal, but in case throttling is employed in front of the compressor, p_0 will be lower than p_4 .

The advantages of this working process as compared to the working processes known up to now may be seen from the Figs. 2, 3, and 4 containing two sets of curves. On these figures the

ordinate is the compression ratio p_1/p_0 , whilst the abscissa is the proportion in which the pressure drop (p_2-p_0) corresponding to nearly adiabatic expansion stands to the total pressure drop (p_1-p_0) . The abscissa

$$\frac{p_2-p_0}{p_1-p_0}$$

represents accordingly the so-called relative magnitude of the adiabatic expansion. Accordingly, on the first of the two sets of curves the ordinates belonging to the value zero of the abscissa represent the figures corresponding to the isothermal expansion, whilst the ordinates belonging to the value 1 of the abscissa represent the figures belonging to the expansion without further introduction of heat. The curves traced in full lines belonging to one set of curves of the diagram are mutually connecting the points corresponding to an identical thermal efficiency, whilst the curves traced in broken lines, belonging to the other set of curves, are mutually connecting the points corresponding to certain constant figures of useful output of work (specific output of work) expressed in calories per kilogram of air drawn in. With starting data differing from the figures of temperature and of efficiency assumed (see Figs. 3 and 4 as compared with Fig. 2) the curves are of slightly different shape, but in other respect of generally similar character.

It appears from the diagram of Fig. 2 belonging to a compressor efficiency of 0.85 and a turbine efficiency of 0.9, further to a maximum temperature of 600° C., that with a certain advantageous compression ratio, e. g. between $p_1/p_0=5$ and $p_1/p_0=11$, a thermal efficiency slightly more advantageous than 25% may be obtained also by means of a process of work operating with purely adiabatic expansion, but the specific performance will only amount to a figure between 24 and 17 calories per kg. If, as against this, after a section of expansion of a certain length at constant temperature, the introduction of heat is discontinued and the expansion is continued adiabatically, i. e. if the length of adiabatic expansion is shortened as compared to the known process, substantially more advantageous thermal efficiencies and specific outputs are obtained. Thus for instance if the pressure ratio of the compression p_1/p_0 amounts to 15, whilst the relative length of adiabatic compression is 0.17, the thermal efficiency will amount of 30.5% and the specific work to 40 cal./kg. By further diminishing the relative length of the adiabatic expansion, whilst keeping the ratio of compression p_1/p_0 constant, the efficiency will become lowered, but the specific output becomes improved still further. In view of the fact that the increase of the specific output is accompanied by a diminution of the own weight of the mechanism, it is from this point of view advantageous to employ a relatively short adiabatic expansion.

With the conditions illustrated on Figs. 3 and 4, belonging both to a compressor efficiency of 0.9 and a turbine efficiency of 0.95, further to a maximum temperature of 600° C. and 700° C., respectively, the above considerations are, although with slightly different numerical values, valid likewise.

The smallest permissible length of the adiabatic expansion will be determined by the consideration that the combustion should certainly become completed already before discharge from the turbine, because any part of the fuel the combustion of which is effected after it has left the

turbine represents a loss. Thus it will be preferable to employ an adiabatic expansion the relative length of which

$$\frac{p_2-p_0}{p_1-p_0}$$

amounts to at least 0.05. The increase of the length of the adiabatic expansion—whilst keeping the ratio of compression constant—will be beyond a certain limit cause a diminution in efficiency as well as in specific performance of work; the specific performance will, however, diminish at a more rapid rate than the efficiency. The permissible maximum of the relative length of the adiabatic expansion can in the case of a greater ratio of compression not be as high in the case of a smaller ratio of compression because in this case the specific performance will become diminished more rapidly with the increase of the figures

$$\frac{p_2-p_0}{p_1-p_0}$$

For this reason the employment of a relative magnitude of adiabatic expansion expressed as a function of the pressure ratio exceeding a certain figure is unadvisable, and as a result of the examination of these three diagrams can be stated that from the points of view of the invention it is advisable to choose the relative magnitude of the adiabatic compression, i. e. the figure

$$\frac{p_2-p_0}{p_1-p_0}$$

so as to be smaller than the figure resulting from the formula

$$\frac{92-p_1/p_0}{88}$$

This result is obtained in the way that a boundary line, represented analytically by this formula, may be traced in the diagrams (as shown e. g. in Fig. 4 by the line *a—b*) beyond which line the conditions are unsatisfactory as regards the points of view explained above.

It also appears clearly from the curves of Fig. 2 that in case of the employment of adiabatic expansion of a magnitude of about 4/10, the efficiency is nearly independent of the length of the adiabatic expansion. For this reason it is advisable to proceed in such a manner when regulating the output of the gas turbine that whilst keeping the maximum temperature at a nearly invariable figure, the quantity of heat introduced is regulated by altering the magnitude of the adiabatic part. It is, however, also possible to proceed, differently herefrom, in such a manner, that at the regulation the maximum temperature, i. e. the specific quantity of heat introduced at constant pressure is also varied. If it is desired to avoid that the temperature should become excessively diminished with the diminution of the output, it is also possible to proceed in such a manner, as to diminish the quantity of air supplied by the compressor by means of throttling, simultaneously with diminishing the quantity of heat introduced, which can be done by means of a simple throttling member employed in front of the compressor.

In Fig. 5 an embodiment of the gas turbine suitable for putting the working process according to the invention into effect is shown by way of example. In the embodiment shown by way of example on this drawing the compressor rotor 3 carrying the rotor blades 2 is keyed jointly with the turbine rotor 5 carrying the turbine blades 4

on the turbine shaft 6 supported in the bearings 25, 26, both rotors being arranged inside the compressor and turbine casing 1. Stationary blade rings 7 are located between successive blade rings of the compressor rotor, whilst stationary turbine blade rings 8 are located between the successive rotor blade rings of the turbine. The combustion space 9 into which the burners or atomizers 10-10' are opening, is arranged behind the compressor.

Further, the burners or atomizers 11, 12 for the introduction of fuel are likewise arranged between the successive blading stages of the turbine. The combustion space 9, the transverse section of which is shown on Fig. 5a, is in the embodiment shown by way of example constituted by the interior of an annular hollow body (combustion chamber) 13 having a meridian section as shown on the figure, which is mounted in the turbine casing coaxially with the turbine axis, and the walls of which are—apart from a number of places of support—not entirely supported on the wall of the gas turbine casing, a clearance or channel 14 being left between them and the said gas turbine casing wall. The interior of the combustion chamber is fitted with openings communicating with the space 15 leading from the compressor into the turbine and is fitted with the guiding or deflecting members 16 which stand opposite to the current of gas coming from the compressor. These guiding members may be shaped in the manner of a system of teeth preferably bent against the direction of flow of the gas current, and distributed over the whole periphery or located on certain parts of the periphery only, but they may possibly also be dispensed with entirely.

The feeding of the fuel injection members 10, 10', 11, 12 etc. is effected e. g. by the reciprocating pump 22. If it is desired that the feeding should not be periodical, the balancing chests 23 e. g. air chests per se known and commonly used in connection with reciprocating pumps may be inserted between the pump and the fuel injection members. The connection between the pump and the fuel injection members is effected by the ducts 24. The number and arrangement of the burners or atomizers employed for the purpose of introduction of heat are shown on the drawing in a diagrammatical manner only and may also be different from those shown. The manner of operation of this apparatus is the following: In case of the rotation of the shaft 6 the compressor will draw in air in the direction of the arrow 17 through the inlet openings 18 and will compress this air by making it flow through the blade rings.

The members 10, 10' for the introduction of fuel are either leading hot gases of combustion into the combustion space 9 or directly passing the fuel into the said space; in the case of liquid fuel they are atomizing the latter; in the case of solid fuel it is not by means of atomizing but by some other means that the said members allow the fuel to pass into the space 9, whilst in the case of gaseous fuel the fuel, possibly already previously mixed with air will simply flow in through these members. The same is true also for the burners, or, as the case may be, atomizers 11 and 12 for the introduction of fuel. Owing to the introduction of heat by the members 10, 10' the temperature of the compressed air will become increased at constant pressure during the combustion, following which inflow into the turbine part will take place. In the turbine stages the gas will gradually expand and will be discharged from

the turbine in the direction of the arrow 19 through the discharge opening 20. The purpose and operation of the combustion chamber 13 shown on Fig. 5 will be the following: the air leaving the compressor is flowing rapidly and therefore, unless a furnace space of sufficient magnitude is provided between the compressor and the turbine, insufficient time would be available for the combustion of the fuel at the desirable rate. On the other hand, it is all the more necessary to make provision for the rapid combustion of the fuel because it is not in each case that the temperature of the air discharged from the compressor is high; in the case of a compression to ten times the original pressure

$$\left(\frac{p_1}{p_0} = 10 \right)$$

and in case the air drawn in has a temperature of 0° C., the temperature reached after compression is about 300° C., at which temperature, for instance in the case of operation on gas-oil, the time required for the ignition of the fuel will be quite considerable. The opening of the chamber 9 through which the said chamber communicates with the flow space 15 is washed by the current of air, and in that embodiment of the apparatus according to the invention in which the guiding members 16 are wanting, the current of air will set the gas contained in the combustion chamber into rotation owing to friction whereby a layer of the air current adjacent to the rotating gas mixture will be detached and carried away into the combustion chamber, so that the entrance of fresh air into the combustion chamber will be assured in this case also, in consequence of which a corresponding quantity of gas mixture will be displaced herefrom towards the entrance into the turbine. The same result is obtained and increased by the employment of the guiding members 16, which are at certain places deflecting a part of the air current into the combustion chamber where the fresh air entering the chamber maintains a turbulent circulating motion. By selecting the magnitude of the communication opening in a suitable manner, and/or by giving a suitable shape to the guiding members it is possible to control the portion of the air supplied by the compressor which should enter the combustion chamber. The fuel is led into the combustion chamber by means of the members 10, 10' which are shaped in such a manner as to ensure the proper mixing of the fuel, this being done in the case of liquid fuel by means of atomizers; in the said combustion chamber the combustion is taking place in such a degree as required according to what has been explained above. In view of the fact that it is only in a portion of the total quantity of air entering the combustion chamber that combustion takes place, the temperature ruling in the combustion chamber will be substantially higher than the average temperature of inlet into the turbine, and thus it will be possible to make satisfactory provision for self-ignition and for ensuring that the combustion should take place in a suitable degree before entrance into the turbine without raising the average temperature above the limit permissible in view of the heat resistance of the turbine structure. Thus if, for instance, the temperature of the gas leaving the compressor is 300° C., whilst that of the gas entering the turbine amounts, on the average, to 600° C., the rise of temperature during the combustion taking place at constant pressure will

amount for the whole volume of gas to 300° C. If one-third of the fresh air discharged from the compressor is allowed to enter the combustion chamber the temperature rise in this portion of the air will be $3 \times 300 = 900$ ° C., whilst the temperature ruling in the combustion chamber will be 1200° C., at which temperature the ignition and combustion will already take place very rapidly.

In order to ensure that the walls of the combustion chamber should not become excessively heated or should not heat the wall of the casing excessively, it will be advisable to allow a part of the air to flow through the clearances or ducts 14 left between the combustion chamber and the casing. The guidance of the air into this clearance is effected by means of the guiding member 21 which projects in the desired extent into the stream of air and directs a flow of suitable intensity towards the clearance. It is, however, also possible to insulate the wall of the combustion space by other means.

From the combustion chamber a quantity of hot gas corresponding to the quantity of air flowing in will flow out, which quantity of hot gas will accordingly become mixed with the rest of the current of air already before entering the turbine, so as to prevent that the turbine blades should become excessively heated at single places. Provision for the thorough mixing of the hot gases discharged from the chamber with the rest of the air should be made by leaving free a suitable mixing space as shown at 15 in Fig. 5.

As appears from the above it is a circumstance of great importance from the point of view of safe ignition and combustion, and on the other hand from the point of view of the proper moderation of the initial temperature of entrance into the turbine, that the current of air issuing from the compressor and entering the combustion chamber is divided into two parts, the combustion taking place first in one of these parts, whilst the other part serves for the reason referred to for the purposes of the admixture after combustion.

The fuel-introducing devices 11 and 12 which may of course be arranged not only in the second and third stage but in any desired number and at any desired places are serving for the supplementary introduction of fuel for the purpose of carrying the isothermal or approximately isothermal expansion into effect. These atomizers are however not required in each case. It is also possible to carry the isothermal expansion into effect in such a manner that it is only into the combustion space 9 that any fuel is introduced, notably in such a manner, that the combustion is not completed before inlet into the turbine, but should be continued in the turbine so as to produce the isothermal or approximately isothermal expansion. In order to carry isothermal combustion into effect the manner in which the fuel is passed into the combustion space possesses extraordinary importance. How much fuel will be burned before entering the turbine and how much will be burned before entering the turbine and how much will be burnt in the turbine itself, is a matter which can be controlled by means of the perfection of the mixture, in the case of liquid material by the extent of atomization as well as by the selection of the particular place of the space of combustion at which the fuel is passed into the air, and furthermore also by the shape and/or dimensions given to the space of combustion. All effects by which

combustion is slowed down, will also extend the length of the section along which isothermal expansion takes place. Thus it will be advisable to select and/or feed the atomizers, including the atomizers feeding into the combustion chamber, in such a manner, as to ensure that the degree of fineness of their atomization should be different. Fuel atomized into fine particles will become burnt more quickly than fuel atomized into rough particles only and according to the degree of fineness of the atomization the combustion will extend into the turbine in a greater or in a less degree. At a certain degree of atomization, it is moreover possible to influence the progress of the combustion also by means of the shape given to the combustion chamber 9, and/or by means of the quantity of the fresh air introduced into the said chamber.

Should in the regulation of the gas-turbine the length of the isothermal section also be varied, it is preferable to vary at least one among the factors mentioned above. It is for this purpose that the constructional detail shown on Fig. 7, which represents an atomizer, serves. In the atomizer body 33 the valve 34 sliding in a tight manner preventing leakage is arranged, which valve by means of its conical end is regulating, according to the position occupied by the said valve, the cross section left open in the conical opening 36. It is through the bore-holes 37 and 38 that the fuel enters the atomizer body from which it passes into the storage space 39. In the storage space 39 the pressure of the fuel is such, that by acting on the lower surface of the valve 34 it will raise the said valve against the action of the spring 40. The preliminary tension of the spring 40 is controlled by adjusting the screwed spring support 41 in the longitudinal direction by turning the handle 42. As the degree of atomization of the fuel depends on the pressure of the atomization, the amount of atomizations can also be controlled by turning the handle 42.

If the fuel is injected into the chamber of combustion by means of a plurality of atomizers, it will be preferable to effect regulation in case of the diminution of the output in such a manner, that it is the feeding of the atomizers operating with a more rough atomization which is diminished first; whilst if in addition to the atomizers or fuel introducing burners feeding into the chamber of combustion fuel is introduced also by means of burners or atomizers arranged between the various stages of the turbine, it is in the first place the feeding of these last named burners or atomizers which is reduced in case of a diminution of the output.

In case during the course of the regulation of the gas turbine the air drawn in is throttled, it is necessary to arrange the throttling members, e. g. the throttle-valve 14 (Fig. 6) in the inlet opening of the compressor.

The axial throughflow compressor and axial throughflow turbine shown on Fig. 5 are particularly advantageous for carrying the working process forming the subject of the invention into effect, because they permit the throughflow of a very large quantity of air with small dimensions of the apparatus, such small dimensions meaning at the same time a small weight of apparatus. This apparatus will, particularly in the case of such a design in which it is substantially only the components of peripheral direction of the gas velocity which suffer any alteration, (in which accordingly, no alteration is suffered owing to the changes of energy by the axial

component) permit very high throughflow speeds without substantial losses deriving therefrom. It is characteristic for a compressor and/or turbine of such a type of design that the mean blade circle diameter of a stationary blade ring arranged between two adjacent rotating blade rings is approximately or exactly similar to the mean figure of the blade circle diameter of the rotating blade rings. It is, moreover, also characteristic that the individual blade rings are arranged immediately alongside each other without any partition wall being provided between them.

In connection with the compressor it is, in order to obtain a particularly high efficiency and high output, preferable to make provision for removing the spent boundary layer braked owing to friction and to rise of pressure from the surface of the casing and/or of the rotor, so as to avoid the expected rise of pressure being prevented by the said layer. It is for this purpose that the arrangement per se known, shown by way of example in Fig. 5, serves, in which the spent boundary layer is through the ports 28, 28', provided along the partition walls 27, 27' in some stage of the compressor, flowing back through the ducts 29, 29' and through ports 30, 30' to a place of lower pressure of the compressor, entering into which place it will possess the regular contents of energy relatively to the conditions ruling there, and thus it will not be able to hinder that the rise of pressure should take place.

In view of the fact that the higher the temperature at which the turbine is operating, the higher will be its efficiency, and the greater the peripheral velocity of its rotation, the smaller will be the dimensions of the turbine, the mechanical stresses to which the material of the rotor is subjected will also be substantial. For this reason it will be preferable to cool the rotor from inside. This can be carried into effect in a suitable manner, if a current of air is allowed to enter the interior of the rotor, and it is this purpose which is served by the openings, shown on Fig. 5, on the one hand in the rotor at 31-31' and on the other hand in the bearing pedestals of the casing at 32, 32'.

In addition hereto it is possible to cool the turbine rotor also by means of the compressed air leaving the compressor, or by means of a portion of such air, the said portion, in this case, participating in the working cycle of the turbine after having passed through the interior of the turbine rotor. Moreover the external casing of the turbine also can be cooled by means of the compressed air.

This last-named arrangement of the cooling of the turbine rotor is shown on Fig. 6, according to which it is between the compressor rotor 61 keyed on the shaft 60 and the disc-shaped turbine rotor 62, 62' keyed likewise on the shaft 60 that the combustion chamber 63 is arranged; the latter, however, is in the present type of design not inserted closely between the rotors, but leaves room for the air conducting gaps 65 and 66 respectively. On the rotating discs of the turbine there are provided in the vicinity of the shaft the openings 67, 67' . . . , beyond which openings, on a larger diameter, the ribs 68, 68' . . . are provided. The annular ribs of the mutually adjacent discs are either not in mutual contact at all, or are in mutual contact in places only, so that a throughflow cross-section remains for the air. Beyond the annular ribs, on a diameter larger still, further throughflow openings 69, 69' . . . etc. are provided in the discs. On

that side of the combustion chamber 63 which faces the compressor there is provided opposite to the current of air leaving the compressor, and in such a manner as to project into this current of air, the guiding edge 70, which is able to divide the current of air leaving the compressor into two portions. The combustion chamber is fixed into the external casing 71 by means of the guiding members 72, which guiding members—as already described in connection with Fig. 5—are arranged on various parts of the periphery of the combustion chamber and are intended for guiding the air into the combustion chamber.

On the side facing the turbine of the combustion chamber body the ring rib 73 is closely approaching the first disc of the turbine rotor, so that only a small clearance remains between the two. The operation of this mechanism is the following: The current of air issuing from the compressor will, in accordance with the arrows marked on the drawing, after striking against the guiding edge 70, flow partly towards the combustion chamber, and partly flow inward in a radial direction alongside the combustion chamber through the duct 65. This part of the air current is the cooling current which will enter the turbine rotor in the axial direction through the openings 67, 67' provided in the discs, but will flow outwards along the turbine discs through the clearances or openings left between the ring ribs 68, 68' of the discs, and will thereby efficiently cool the external surface of the said discs. The current of air returns into the space remaining between the turbine rotor and the chamber of combustion through the return bore-holes 69, 69', following which it will through the duct 66 flow into the turbine, mixed into the rest of the working medium.

It is at the point of entrance into the compressor, and in the low-pressure part of the turbine that the specific volume of the gas flowing through the gas turbine is the highest. In order to prevent that, particularly at the last-named place, an excessively long radial blade dimension should result, it is preferable to construct the turbine in such a manner that its low-pressure part should be of greater diameter. In order to prevent, on the other hand, that in this case its peripheral velocity should be too high, it is advisable to fix the speed of the low-pressure part at a lower figure. Such an arrangement is illustrated by Fig. 8. As shown in this figure, it is in the casing 43 that the rotor 44 of the turbine-compressor set is arranged, the said rotor being mounted so as to be rotatable in the bearings 47-47', on the shaft 46 of the low pressure turbine rotor 45, which latter drives the energy consumer (e. g. the airplane air propeller 57) in a direct manner.

The shaft 46 is supported by means of the bearings 48, 48, in the casing 43. The air flows in at the inlet opening 49 of the compressor, following which it flows through the compressor 50 and through the high-pressure turbine 50 and proceeds into the low-pressure turbine 45 of greater diameter. A mechanical connection is effected between the rotors 44 and 45 by the gear 51.

In Fig. 9 the low-pressure rotor 52 of the compressor is likewise of greater diameter than the high-pressure rotor 53, and is keyed on a common shaft 56 with the compressor rotor 54 of the turbine, as well as with the consumer (air propeller) 57. Here the mechanical connection with

the turbine-compressor set 53 is supplied by the gear wheel 55.

It is preferable to select the dimensions of the compressor-turbine set 44, or 53, respectively, and/or the distribution over high-pressure and low-pressure parts in such a manner that the resultant useful output of the part containing the high-pressure turbine (turbine and compressor) should be zero, i. e. that the work of the turbine should just cover the requirements of energy of the compressor. In such a case it is preferable to take off the useful output at the shafts 46 or 56, respectively, and thus the output to be transmitted by the gears 55 or 51, respectively, is likewise zero, or only very small. By driving the machines in such a manner the mechanical connection between the compressor-turbine set and the low-pressure machines may also be dispensed with entirely, in which case the former rotates freely.

It is understood that the arrangements described and illustrated by the drawings should only be considered to represent embodiments shown by way of example, innumerable other variants of arrangement being likewise suitable for carrying the process forming the subject of the invention into effect, and it is only for the sake of brevity that such other variants of arrangement have not been described and illustrated in detail.

I claim:

1. A process for gas turbines, consisting in effecting the introduction of heat by introducing fuel into the compressed working medium and burning a part thereof in a part of the working medium, i. e. so as to concentrate combustion to a portion of the working medium only, before the inlet into the turbine and by burning another part of the fuel during expansion, in the gas current formed by the totality of the working medium, in the turbine itself, advantageously at a practically constant temperature, and in following this latter fuel combustion by a further expansion approaching more the adiabatic than the isothermal, preferably without any heat introduction.

2. A process for gas turbines, consisting in effecting the introduction of heat into the compressed working medium by introducing and burning fuel in a combustion chamber, being arranged between the compressor and the turbine and suitable for holding only a part of the working medium, at constant pressure and thereafter by introducing and burning a further quantity of fuel in the gas current flowing in the turbine in a manner and distribution as to ensure by its combustion advantageously approximately isothermal expansion, until an intermediate turbine stage, and in following this latter fuel combustion by an expansion, approaching more the adiabatic than the isothermal, preferably without any heat introduction.

3. A process for gas turbines, consisting in admitting the fuel and a part of the compressed combustion air entering the turbine to a combustion space of constant pressure between the compressor and the turbine in a manner and quantity ensuring the commencement of the combustion in the said combustion chamber and the continuation thereof in the gas current formed by the totality of the working medium, in the turbine itself, until an intermediate turbine stage, advantageously at approximately isothermal expansion, this section of expansion being followed by a further expansion approach-

ing more the adiabatic than the isothermal, preferably without any heat introduction.

4. A process for gas turbines, consisting in effecting the introduction of heat by introducing fuel into the compressed working medium and burning a part thereof in a part of the working medium, i. e. so as to concentrate combustion to a portion of the working medium only, before the inlet into the turbine and by burning another part of the fuel during expansion, in the gas current formed by the totality of the working medium, in the turbine itself, advantageously at a practically constant temperature, and in following this latter fuel combustion by a further expansion approaching more the adiabatic than the isothermal, preferably without any heat introduction, the magnitude of the expansion without any heat introduction being chosen so as to keep the relative magnitude

$$\frac{p_2 - p_0}{p_1 - p_0}$$

of this expansion (the proportion of the pressure drop $p_2 - p_0$ thereof to the full pressure drop $p_1 - p_0$ in the turbine) between the limits 0.05 and

$$\frac{92 - p_1/p_0}{88}$$

5. A process for gas turbines, consisting in effecting the introduction of heat by introducing fuel into the compressed working medium and burning a part thereof in a part of the working medium, i. e. so as to concentrate combustion to a portion of the working medium only, before the inlet into the turbine and by burning another part of the fuel during expansion, in the gas current formed by the totality of the working medium, in the turbine itself, advantageously at a practically constant temperature, in following this latter fuel combustion by a further expansion approaching more the adiabatic than the isothermal, preferably without any heat introduction, and in altering the relative magnitude

$$\frac{p_2 - p_0}{p_1 - p_0}$$

of this further expansion (the proportion of the pressure drop $p_2 - p_0$ thereof to the full pressure drop $p_1 - p_0$ in the turbine) with the alteration of the heat quantity introduced when the output of the turbine is altered.

6. A process for gas turbines, consisting in effecting the introduction of heat by introducing fuel into the compressed working medium and burning a part thereof in a part of the working medium, i. e. so as to concentrate combustion to a portion of the working medium only, before the inlet into the turbine and by burning another part of the fuel during expansion, in the gas current formed by the totality of the working medium, in the turbine itself, advantageously at a practically constant temperature, in following this latter fuel combustion by a further expansion approaching more the adiabatic than the isothermal, and in throttling the air to be compressed simultaneously with the diminution of the heat quantity introduced when the output of the turbine is diminished.

7. A process for gas turbines, consisting in admitting the liquid fuel and a part of the compressed combustion air entering the turbine to a combustion space of constant pressure between the compressor and the turbine in a manner and quantity ensuring the commencement of the combustion in the said combustion chamber

ber and the continuation thereof in the gas current formed by the totality of the working medium, in the turbine itself, until an intermediate turbine stage, advantageously at approximately isothermal expansion, in following this expansion with a further expansion without any heat introduction, and in altering the degree of atomization of the fuel in the combustion air when the output of the turbine is altered.

8. A process for gas turbines, consisting in admitting the liquid fuel, by means of atomizers, and a part of the compressed combustion air entering the turbine to a combustion space of constant pressure between the compressor and the turbine in a manner and quantity ensuring the commencement of the combustion in the said combustion chamber and the continuation thereof in the gas current formed by the totality of the working medium, in the turbine itself, until an intermediate turbine stage, advantageously at approximately isothermal expansion, and in diminishing firstly the fuel supply of the atomizers supplying between the turbine stages when the output of the turbine is diminished, the said section of expansion being followed by a further expansion approaching more the adiabatic than the isothermal, preferably without any heat introduction.

9. In an equipment for gas turbines, a compressor for compressing the working medium, a gas turbine, a combustion chamber between the said compressor and turbine suitable for holding only a part of the compressed working medium, and means introducing fuel into the compressed working medium in a manner ensuring combustion of a part of the fuel before the inlet of the turbine in the said combustion chamber, and of the remaining part of the fuel, until an intermediate turbine stage, in the turbine also, this latter fuel combustion being effected advantageously at isothermal expansion, and accompanied by a further expansion approaching more the adiabatic than the isothermal, preferably without any heat introduction.

10. In an equipment for gas turbines, a compressor for compressing the working medium, a gas turbine, an annular hollow body around the turbine shaft forming the combustion chamber between the said compressor and turbine, suitable for holding only a part of the compressed working medium, an annular inlet opening on the said hollow body close to the current of working medium flowing from the compressor towards the turbine, means suitable to deflect at least a part of the working medium current into the combustion chamber, situated on the edge of the said annular inlet opening facing the flow and means supplying fuel at least partly into the said combustion chamber in a manner and distribution ensuring combustion partly before the inflow into the turbine, and partly in the first stages of the turbine also, this latter combustion being effected advantageously at isothermal expansion.

11. In an equipment for gas turbines, a compressor for compressing the working medium, a gas turbine, an annular hollow body around the turbine shaft forming the combustion chamber between the said compressor and turbine, suitable for holding only a part of the compressed working medium, an annular inlet opening on

the said hollow body close to the working medium current flowing from the compressor towards the turbine, a by-pass air gap between the said hollow body and the engine casing, wall prolongations projecting into the compressed air flow and deflecting a part thereof into the said gap, provided on the edge of the inlet opening of the combustion chamber nearer the compressor, means suitable to deflect at least a part of the remaining quantity of the working medium current into the said combustion chamber, situated on the edge of the said annular inlet opening nearer the turbine, and means supplying fuel into the working medium at best until an intermediate stage of the turbine in a manner and distribution ensuring combustion partly before the inflow into the turbine in the said combustion chamber, and partly during the first part of the expansion in the turbine also, this first part of expansion being effected advantageously isothermically.

12. In an equipment for gas turbines, a compressor for compressing the working medium, a gas turbine fed with liquid fuel, a combustion chamber joining on to the flow path of the working medium between the said compressor and turbine suitable for holding only a part of the compressed working medium streaming to the inlet into the turbine, and atomizers of different degree of atomization for supplying the fuel into the said combustion chamber and into the first stages of the turbine in a manner ensuring combustion and approximately isothermal expansion until an intermediate expansion stage.

13. In an equipment for gas turbines, a compressor for compressing the working medium having blade rows of average diameters equal to the mean figures of the average diameters of the adjacent blade rows, a gas turbine, a combustion chamber joining on to the flow path of the working medium between the said compressor and turbine suitable for holding only a part of the compressed working medium streaming to the inlet into the turbine, and means introducing fuel into the compressed working medium in a manner ensuring combustion to be started before the inflow into the turbine in the said combustion chamber and completed in an intermediate expansion stage of the turbine, the combustion in the turbine being effected advantageously at isothermal expansion.

14. In an equipment for gas turbines, a compressor for compressing the working medium having blade rows of average diameters equal to the mean figures of the average diameters of the adjacent blade rows and channels in the walls of its working space connecting zones of lower and higher pressure, a gas turbine, a combustion chamber joining on to the flow path of the working medium between the said compressor and turbine suitable for holding only a part of the compressed working medium streaming to the inlet into the turbine, and means introducing fuel into the compressed working medium in a manner ensuring combustion to be started before the inflow into the turbine in the said combustion chamber and completed in an intermediate expansion stage of the turbine, the combustion in the turbine being effected advantageously at isothermal expansion.

GEORGE JENDRASSIK.
